US00D883635S

(12) United States Design Patent (10) Patent No.: US D883,635 S
Hatfield et al. (45) Date of Patent: * May 12, 2020

(54) SHOE

(71) Applicant: NIKE, Inc., Beaverton, OR (US)

(72) Inventors: Tobie D. Hatfield, Lake Oswego, OR (US); Carl L. Madore, Portland, OR (US)

(73) Assignee: NIKE, Inc., Beaverton, OR (US)

() Term: 15 Years

(21) Appl. No.: 29/666,050

(22) Filed: Oct. 9, 2018

(51) LOC (12) Cl. 02-04

(52) U.S. Cl.

USPC D2/960; D2/951; D2/953

(57) CLAIM

The ornamental design for a shoe, as shown and described.

DESCRIPTION

FIG. 1 is a front perspective view of a shoe showing our new design;

FIG. 2 is a bottom view thereof;

FIG. 3 is a rear perspective view thereof;

FIG. 4 is an enlarged view of FIG. 1 with environment removed for clarity purposes;

FIG. 5 is an enlarged view of FIG. 2 with environment removed for clarity purposes; and,

FIG. 6 is an enlarged view of FIG. 3 with environment removed for clarity purposes.

The broken lines immediately adjacent to the shaded areas define the bounds of the claimed design and form no part thereof. The broken lines depicting the remainder of the shoe show features that form no part of the claimed design.

1 Claim, 6 Drawing Sheets
